UNITED STATES PATENT OFFICE

AUSTIN A. OVERBURY, OF WEST ORANGE, NEW JERSEY, ASSIGNOR TO MONROE CALCULATING MACHINE COMPANY, OF ORANGE, NEW JERSEY, A CORPORATION OF DELAWARE

REGISTER

Application filed September 5, 1929. Serial No. 390,598.

The invention has relation to means for clearing out, or setting to zero, the registering wheels of an adding or calculating machine, the invention comprising improved motor 5 driven means for this purpose.

The invention consists in the novel construction and combination of parts, as set forth in the appended claims.

In the accompanying drawings, illustrating the invention:

Figure 1 is a plan view of a calculating machine to which the invention is shown as applied.

Fig. 2 is a plan view of the motor and clear- 15 out drive train.

Fig. 3 is a right side elevation of the clear- out mechanism.

Fig. 4 is a similar view of the parts hidden in Fig. 3.

Fig. 5 is a right side elevation of the swinging calculator gear frames and associated parts.

Fig. 6 is a detail face view of the safety latching mechanism.

The invention is shown as applied to well known Monroe calculating machines, but is capable of use with other registers of widely differing design.

In the drawings, the numeral 1 designates 30 the stationary frame of the machine, and 2 the transversely shiftable carriage whereon the plurality of registers are mounted. As shown, these registers comprise two sets of accumulator wheels 3 and 4, mounted on 35 parallel shafts and two sets of counting wheels 5 and 6, mounted on a single shaft, parallel with the shafts of the wheels 3 and 4.

Power for clearing the various registers is derived from the motor 7, (Fig. 2), having 40 drive connection 8 with a shaft 9 whereon a sleeve 10 is mounted, said sleeve having a friction drive connection 11 with shaft 9. Sleeve 10 has gearing connection 12 with a shaft 13 constituting the drive shaft of 45 the clearing mechanism.

A series of clear keys 14 (Fig. 3) is provided, one key for clearing each of the registers 3 and 4, and one key for clearing both 50 registers, 5 and 6. A key 15 is also provided,

whereby all of the registers may be cleared simultaneously.

Each of the keys 14, upon depression, is adapted to impart rearward sliding movement to bars 16, one of the bars being provided for each key. The bars 16 are pivoted to the lower arms of bell cranks 17, the upper arms of which are contacted by shoulders 18 of the keys. Each of the bars 16 is further provided with a lug 19, which, in the rearward sliding movement of the bars, will contact with a member 20, common to the lugs 19 and mounted upon a pivoted member 21. Through members 20 and 21, rearward movement of a bar 16 will depress a plunger 22 and will, by means of a pin 26, rock a lever 23, having a roller 24, which will act to close the electric contact members 25 and establish an electric circuit through motor 7. Lever 23 will be held in circuit closing position by means of a spring latch 27.

Downward movement of plunger 22 will also rock an arm 28 out of engaging relation with the clutch arm 29 (Fig. 4) fast with the pivotal clutch member 30. Member 30 is mounted in the driven plate 31 and has the well known cut-away portion through which driving shaft 13 is adapted to pass. Upon release of part 29 by arm 28, a suitable spring 30 will rotate the clutch element 30 causing said element to enter a semi-cylindrical recess of shaft 13, whereby the driven plate 31 will be clutched to the drive shaft. A Geneva gear 32 is fast with plate 31, and upon the engagement of the clutch above described, gear 32 35 will set in motion a train of gearing 33 to drive a gear 34, mounted upon the shaft 35 of carriage 2. Gear 34 is splined to shaft 35, and is held in fixed relation to the gear train 33 by means of suitable guide members, so that carriage 2 may be shifted laterally without bringing gearing 34 out of mesh with said train. A second gear train 36, in the carriage 2, transmits the movement to gears 37, 38, and 39, fast with the shafts of the registers to be cleared.

The bars 16 are adapted to set clearing members into active position, whereby one or all of the registers will be set to zero upon 100

rotation of the register shafts, this means comprising a bell lever 40 having a roller riding upon the cam surface of disc 31. A pin 41 of said bell lever underlies the bars 16, and acts in the rotation of the disc 31 to raise the rearward end of said bars, and thereby to bring dogs 42 of the rearwardly moved bars into contact with plungers 43. At their upper ends plungers 43 contact each 10 with one of a series of clearing fingers 44 fastened upon rock shafts 45, so that upward movement of the plungers will move fingers 44 into the path of movement of pins 46 of the register wheels. The register wheels 15 are frictionally mounted upon their shafts, so that when the pins 46 are brought into contact with fingers 44, the wheels will be held in this position during the balance of the rotation of the register shaft and the 20 character "0" on the wheels will be brought beneath the eight openings of carriage 2. Each of the bars 16 has a dog 42 adapted to operate the above-described parts related to a given register shaft, whereby the register 25 to be cleared will be selected by means of the appropriate key 14. The key 15, for clearing all of the registers by a single key depression, is provided with a bar 48 having a lateral extension 47 engaging all of the lugs 30 19, to move all of the dogs 42 to operative position. The bar 48 is extended rearwardly over pin 41.

At the end of a complete rotation of the above-described parts, the roller of bell lever 40 will drop to the low portion of its cam and allow the bars 16 to fall, restoring the keys to normal position. Plunger 22 is also released, whereby lever 23 will be free to be returned to circuit breaking position by 40 means of a pin 49 on gear 32. Release of the plunger 22 will also release arm 28 which will be brought again into contact with the member 29, whereby clutch element 30 will be rotated to release the clutch between disk 45 31 and shaft 13.

In the machine illustrated, the differential actuating gears 50 and 51 are connected with the registers 3 and 4 by means of intermediate gears 52 mounted in swinging frames 53 (Fig. 5), these frames being normally latched to hold the gears 52 in active position. When the registers 3 or 4 are to be cleared, it is necessary to unlatch the frames 53 which will then be swung by means of a spring 54 out 50 of connecting position between the gears 50, 51 and the related gears of the registers 3 and 4.

This is accomplished by means of a roller 55 on disc 31, which, upon rotation of said disc will move a lever 56 having a toggle connection with the latch 57 to move the latch out of contact with the latching face 58 of one of the frames 53. The frames are connected by a bar. Upon operation of gears 50 65 and 51, the frames will be relatched in active

position by suitable means forming no part of this invention.

As shown, the tens carry elements 60 are mounted in swinging frame 53 and are connected to the drive of the machine by means 70 of modified Oldham coupling device 61.

In order to insure the proper operation of the various devices controlled by the keys 14, a latch 62 may be provided for the bars 16, as shown in Fig. 6. Latch 62 is normally held 75 in inoperative position by an arm 63, provided with a pin 64 engaged by the lug 65 of any one of the bars 16, in rearward movement thereof, to release the latch from restrained position. The latch will remain in engagement with tooth 66 of the rearwardly moved bar 16 until a pin 67 carried by gear 32 contacts with said latch and moves the same to disengaged position, allowing arm 63 to drop to latch restraining position under the influence of spring 68.

I claim:

1. Resetting means for registers having a plurality of sets of numeral wheels, a power train and a plurality of keys; means common 90 to the keys for energizing said train, and devices individual to the keys for rendering movement of said train operative to clear the numeral wheel set related to the key.

2. Resetting means for registers having a plurality of shafts, numeral wheels mounted thereon, gearing connecting said shafts, a motor and means for connecting the motor to said gearing; a plurality of selectively movable bars, means common to and operable by the movement of any of said bars to establish the motor connection, means operable by said motor for imparting a second movement to said bar, and means selected by the first named movement of a bar and operable by said second movement to reset the numeral wheels of a related shaft in the rotation thereof.

3. Resetting means for registers having a plurality of shafts, sets of numeral wheels mounted thereon, normally inactive abutment means for said wheels, gearing connecting said shafts, a motor and motor keys; means common to said keys for connecting the motor to said gearing, and devices individual to the keys for actuating the abutment means of the numeral wheel set related to the key.

Signed at Orange, in the county of Essex and State of New Jersey, this 27th day of August A. D. 1929.

AUSTIN A. OVERBURY.
